* cited by examiner

Primary Examiner—Ian Simmons*Assistant Examiner*—Eric L Goodman(74) *Attorney, Agent, or Firm*—Buchanan Ingersoll & Rooney, PC(57) **CLAIM**

The ornamental design for a portion of a packaging crate, as shown and described.

DESCRIPTION

FIG. 1 is a perspective view of a portion of a packaging crate showing my new design.

FIG. 2 is an enlarged front perspective view along the encircled portion shown in FIG. 1.

FIG. 3 is an enlarged right perspective view of FIG. 2; and, FIG. 4 is an enlarged left perspective view of FIG. 2.

The broken line showing in the figures is for illustration purposes only and forms no part of the claimed design.
